United States Patent Office

Des. 210,365

Patented Mar. 5, 1968

210,365

VITAMIN TABLET OR SIMILAR ARTICLE

Luther H. Kroninger, Jr., and Dean R. Straka, Evansville, Ind., assignors to Mead Johnson & Company, a corporation of Indiana

Filed Mar. 8, 1967, Ser. No. 6,121

Term of patent 14 years

(Cl. D16—3)

The rear is identical with the front; and the two sides are identical.

We claim:

The ornamental design for a vitamin tablet or similar article, as shown and described.
